S. E. SEAMAN,

DRYING PROCESS,

APPLICATION FILED JUNE 4, 1917.

1,299,791.

Patented Apr. 8, 1919.

Inventor,
Stewart E. Seaman,
By his Attorney,

W. R. Hutchinson.

UNITED STATES PATENT OFFICE.

STEWART E. SEAMAN, OF BROOKLYN, NEW YORK, ASSIGNOR TO SEAMAN WASTE WOOD CHEMICAL COMPANY, OF NEW YORK, N. Y., A CORPORATION OF NEW YORK.

DYING PROCESS.

1,299,791.

Specification of Letters Patent. Patented Apr. 8, 1919.

Application filed June 4, 1917. Serial No. 172,594.

To all whom it may concern:

Be it known that I, STEWART E. SEAMAN, a citizen of the United States, and a resident of the borough of Brooklyn, county of Kings, and State of New York, have invented a new and useful Improvement in Drying Processes, of which the following is a full, clear, and exact description.

My invention relates to improvements in a process of drying more or less finely divided wood, hull-bran, nut shells, cotton seed hulls, cellulose, lignum, or other materials having a distillate worth saving preparatory to subjecting such materials to destructive distillation. In order that the material may have the best chemical yield, it is advisable to have it substantially dry, and furthermore this obviates the difficulty of generating too much steam or other waste gases in the retort. Heretofore, however, difficulties have arisen in connection with drying such materials as sawdust and other finely divided material of the kind specified, in that so much dust is generated that explosions frequently occur and the dried material has been dangerous to handle. On the other hand to get the material into the most desirable shape for the best chemical yield and to be handled to the best advantage in the retort, it is desirable that the material be dried down to a low moisture content, and with my improved process I have been able to dry the material to absolute dryness without danger of explosions and without loss of material.

In carrying out this idea I use a drier which can be of any approved type, but is preferably a rotary drier, and apply direct heat in which the furnace gases of combustion are drawn directly or indirectly through the drier. The wet material to be dried is admitted with the hot combustion gases at one end of the drier, the whole content is withdrawn from the opposite end by an exhauster and then passed through a dust separator of the ordinary or any approved type which permits the waste gases and steam to escape from the top, while the material to be distilled is delivered through the bottom. In this way the charge to be distilled is thoroughly and may be absolutely dried, while it does not come in contact with the atmospheric air, but is fed directly to the retort so that all danger is obviated. This will be understood from the description which fol-

lows, and in which the figures show a form 55 of drying apparatus which can be conveniently used for carrying my process into effect, although other forms of driers can be used if preferred.

Reference is to be had to the accompanying drawings forming a part of this specification, in which similar reference characters indicate corresponding parts in all the views.

Figure 1 is a side elevation partly in section of an apparatus suitable for the intended purpose, and

Fig. 2 is a cross section on the line 2—2 of Fig. 1.

The material which as stated is more or less finely divided, and which is to be distilled, is fed in its moist form or natural condition to the hopper 10, passing through a gate 11 which may be counter-balanced by a weighted arm 12 and passes through the inlet end 13 of a rotary cylindrical drier 14. This drier is arranged to receive at its inlet end the combustion gases from a suitable furnace 15, which can be of any approved type.

Where a rotary drier is used as shown it is preferably provided with some form of lifting blades as 16, which will keep the material stirred up and in the air so that all parts of it can be subjected to the hot gases 85 and so quickly dried.

Any suitable means can be used for rotating the drier, and I have shown a very common form of structure in which the drying cylinder 14 has collars 17 running on supporting 90 trucks 18 and driven by a gear wheel 19, pinion 20 and suitable connection with the driving shaft 21. This structure is not gone into in detail for the reason that it only shows the drier in a general type because 95 other forms can be used.

All the material in the drier is exhausted through an outlet pipe 22 which connects with an exhauster 23, and the latter discharges through a pipe 24 into a separator 100 25. This can be any usual type of separator which permits the waste gases and steam to pass out at the top, while the dust and dried material drops through the bottom, from which point it is fed to the retort by 105 any suitable means. The separator 25 is spaced apart from the drier to such an extent as to preclude the possibility of

sparks or embers being drawn through the drier and into the separator so as to produce explosions, and the exhauster 23 is preferably placed between the drier and the separator. This is important because much fine dust is generated in drying and should be removed at once, the material becomes thoroughly dried, and if any sparks should enter this dried material which is 10 more or less gaseous, or at least is in an explosive condition, disastrous results follow.

After the material is thoroughly dried as stated, I prefer to feed it directly to the retort before it has a chance to absorb any moisture or take fire, and to this end I arrange the inlet of the retort immediately below the discharge from the separator 25, or at least arrange to feed the material directly from the separator to the retort. In the drawing I have shown a convenient way of carrying out this idea. Here the drier is shown in connection with a retort of the kind disclosed in Letters Patent of the United States No. 1,236,885, dated August 14, 1917, but obviously other forms of retort may be supplied from the drier if desired. As shown the dried material issuing from the separator passes into the feed hopper 26 of the retort, and from this hopper it is pushed by the ram or plunger 27 into and through the feed pipe 28 of the retort 29. Thus the air is expelled and the retort sealed. Obviously many other forms of retort and feeding devices might be used without affecting the principle of the invention. It will be seen from the description given that the entire material to be distilled passes through the drier with the gases of combustion from the furnace, and that the entire products both of the material to be dried and from the furnace flue, pass to the separator 25 where the separation takes place as indicated, and so the dried material is 45 never in contact with the outside air. Thus it will be seen that the dust and fine material is confined until it reaches the retort, and as the material is mingled directly with the products of combustion from the furnace it 50 is thoroughly dried, and without waste.

From the foregoing description it will be seen that the form of drier is not very material, but that the essential thing is to have a drying chamber through which the hot products of combustion from the furnace are drawn and to carry through this chamber the material to be dried which is thus subjected to the action of the hot furnace gases.

It will also be noticed that this process is 60 continuous, as the drier serves as a part of a flue through which the hot products of combustion from the furnace are drawn, and the material to be dried whether sawdust or other more or less finely divided material, 65 can be continuously fed to the drier and the

separation goes on continuously in the separator 25.

It will be noticed that the drying chamber or drier 14 can receive the hot gases from any suitable furnace, that the feed of the wet material is at the end of the drier which receives the hot gases, and that the material is exhausted by suction applied to the discharge end of the drier. This is important because in this arrangement the greatest pressure is at the end nearest the exhauster, and so the wet material comes in contact with the hot gases of combustion at their point of highest temperature and the sparks are extinguished by the wet material before they can be carried through the drier to the material which has become thoroughly dried. Where attempts have been made to blow hot gases through the drier with the material to be dried, disastrous results have usually followed because the pressure then is highest at the intake end of the drier and occasionally sparks will fly through and of course ignite and explode the charge. It will be further noticed that this operation is continuous and that it is used in connection with a destructive still, so that the material passing from the separator passes directly to the still through suitable feeding means, which it is not thought necessary to show here, and there is no chance for the material to pick up moisture or to create explosive dusts or combustible material in the surrounding atmosphere.

I claim:—

1. The process of drying more or less finely divided materials which consists in delivering such materials to one end of a drier, discharging the hot gases of combustion from a furnace into said drier near the intake of the material to be dried, drawing the mingled gases and material through the drier by suction applied at the discharge end of the latter, separating the waste gases from the dried material, and feeding the dried material direct to a retort.

2. The process of drying more or less finely divided material which consists of feeding the material to be dried to a drying chamber, drawing the hot gases of combustion from a furnace through such chamber whereby the charge and the hot gases become mingled, exhausting the contents of the drying chamber, and separating the steam and waste gases from the dried charge at such a distance from the drying chamber as will preclude the carrying of sparks to the point of separation.

3. The process of drying which consists in feeding more or less finely divided material to be dried into one end of a drier, discharging the hot gases of combustion from a furnace into the inlet end of the drier, agitating the contents of the drier, exhausting the contents from the discharge end of the drier,

separating the steam and waste gases from the discharge, and feeding the dried material to a retort.

4. The process of drying which consists in 5 continuously passing mingled hot products of furnace combustion and material to be dried through a drying chamber, continuously exhausting the contents of the chamber by suction at the discharge end thereof, separating the steam and waste gases from the 10 dried material, and continuously feeding the dried material to a retort.

5. The process of drying which consists in 15 continuously passing mingled hot products of furnace combustion and material to be dried through a drying chamber, continuously exhausting the contents of the chamber by suction at the discharge end thereof, and separating the steam and waste gases 20 from the dried material at such a distance

from the drying chamber as will preclude the carrying of sparks or excessively hot gases to the point of separation.

6. The process of drying more or less finely divided materials which consists in 25 feeding the material to be dried to a drying chamber, drawing the hot gases of combustion from a furnace through such drying chamber and mingling the furnace gases with the material to be dried, withdrawing 30 the contents of the drying chamber to such a distance as will preclude the presence of sparks or excessively hot gases, and then immediately separating the waste gases and fine dust from the dried material.
